UNITED STATES PATENT OFFICE.

ARTHUR D. F. RANDOLPH, OF NEW YORK, N. Y.

PHOTOGRAPHIC DEVELOPING-TRAY.

SPECIFICATION forming part of Letters Patent No. 518,075, dated April 10, 1894.

Application filed March 18, 1893. Serial No. 466,655. (No model.)

To all whom it may concern:

Be it known that I, ARTHUR D. F. RANDOLPH, a citizen of the United States, residing at New York city, in the county and State 5 of New York, have invented a certain new and useful Improvement in Developing-Trays for Photographers, of which the following is a specification.

The present invention relates to developing 10 trays for photographers; and aims to provide a device in which a plate after exposure, can be developed, fixed and washed without removing the plate from the tray and which will admit of the process being at all times 15 under the observation of the operator.

The improvement consists of the novel features and the peculiar construction and combination of the parts which will be herein-after more fully described and claimed and 20 which are shown in the annexed drawings, in which—

Figure 1 is a top plan view of a developing tray of my invention, a portion of the top being broken away to show more clearly the 25 details of the interior construction. Fig. 2 is an end view of the invention. Fig. 3 is a section on the line 1—1 of Fig. 1 looking in the direction of the arrow, the funnels being shown in full lines. Fig. 4 is a cross section 30 on the line 2—2 of Fig. 1 looking to the right as indicated by the arrow. Fig. 5 is a side elevation of the invention, as seen from the side having the slots or openings for the entrance of the plates into the tray, part of the 35 door for closing the said slots or openings being broken away, and showing in dotted lines a stand for supporting the device when in use. Fig. 6 is a top plan view of the lower tray. Fig. 7 is a detail view showing the top 40 and bottom edges of the slots in the side of the tray protected by rubber or other suitable material. Fig. 8 is a detail view of the preferred form of funnel especially constructed to have the delivery end of a flexible tub- 45 ing positively connected therewith.

The tray is composed of two parts, an upper and a lower tray 3 and 4, respectively. The upper tray 3 is open at its bottom and closed at its top by a colored glass A which 50 slides in groove α so as to be readily removed for purposes of cleaning. A strip of rubber or other suitable material G is located at the

lower edge of the tray 3 and is held in a groove g . The outer or free edge of this strip G is deflected or bent down so as to touch the 55 plate a' when the latter is in position and obtain a close joint therewith. The tray 3 will be subdivided into two or more compartments as required by one or more partitions. If two compartments are desired, a single partition F is provided. To provide four compartments a second partition F' will be arranged at right angles to the partition F, as shown by the dotted lines in Fig. 1. The number of compartments is immaterial and 55 will depend upon the capacity of the tray and the number of plates to be treated at the same time. The tray or each compartment thereof will have a spigot m , said spigot being bent to exclude light, which is 60 arranged as near as possible to the plane of the strip G to drain off the fluids used to develop, fix and wash the plates. In addition to a spigot, the tray or each compartment will have two funnels D and D' for the 65 introduction of the solutions or fluids into the tray necessary in the treatment of the plates after exposure to produce the picture. One funnel D is for the developing fluid the 70 other funnel D' for the hypo. After the picture has been developed, washed and fixed the water for washing the plate is admitted to the tray or compartment through either funnel. The spout 5 of the funnel is bent 75 so as to exclude the light and is threaded 80 at its lower end to screw into the side of the tray so as to be readily removed for packing or other purposes. The lower tray 4 is slightly larger than the upper tray 3 to receive the latter and is open at the top and 85 bottom, the latter being closed by a colored glass 6 which is slipped into a groove the same as glass A so as to be readily removed. A ledge or rim K is located on the 90 inner side of the tray about midway between the upper and the lower edges thereof to support the plate a' and the upper tray 3. A strip W of rubber or other like material 95 covers the top and the inner edge of the ledge or rim K to form a packing and obtain a close joint between the plate a' and the said rim or ledge K and prevent injury to the said plate a' . A strip t is arranged on the rim or ledge K and extends around three

sides of the tray or compartment. This strip is narrower than the ledge K and is about as thick as the plate a' and is designed to guide the plate a' in proper place on the ledge when inserting the said plate in the tray to be treated. A slot i in the lower tray opposite the space provided by the omission of the strip t from the fourth side of the tray or compartment admits of the plates a' being inserted and removed from the tray. To prevent injurious contact of the plates a' with the edges of the slot i , the said edges are covered with rubber Q or other suitable material. This material Q extends over the edge of the tray bordering on and forming the slot and embraces the sides thereof, as shown most clearly in Fig. 7. A door R is hinged to the lower tray and extends over the slot i and has a strip M to enter the said slot i and press against the edge of the plate a' and force the latter to proper place when closing the said door. Slots d and d' corresponding in position and number with the funnels and spigots are provided in the upper edge of the lower tray to receive the said funnels and spigots when placing the upper tray in the lower one.

The two trays 3 and 4 are held together and the plate a' clamped between the parts G and W by suitable fastening means as threaded rods C, and thumb nuts B. The rods C are secured to lateral extensions 7 on the lower tray and are adapted to have their upper threaded ends pass through corresponding lateral extensions 8 on the upper tray to receive the thumb nuts B which obtain a bearing upon the said extensions 8 and draw the two trays together and clamp the plate a' between the lower edge of the tray 3 and the ledge or rim K.

The colored glasses A and 6 may be ruby, orange, red or other color that will exclude the actinic properties of light. These glasses permit the operator to watch the process of developing at all times and determine when the same has reached a proper stage.

In using the tray the thumb nuts B are loosened and the upper tray elevated, as shown by the dotted lines in Fig. 4, the plate a' to be developed is inserted through the slot i and the door R is turned up and fastened, the strip M thereon entering slot i and forcing the said plate in position, the thumb nuts B are then turned down to clamp the plate between the tray 3 and the ledge K, making the compartments water tight. The developer is poured in through one of the funnels D and after the plate is sufficiently developed is drawn off through the spigot m. The water is then poured in through the funnels to wash plate. The hypo is now poured in through the other funnel D' and after the picture is fixed the hypo is drawn off and the plate a' washed by admitting water through either of the funnels. The water is likewise drawn off through the spigot m. The preferred form of funnel shown in Fig. 8 has the

upper end of the spout internally threaded to receive a threaded coupling n on the end of a flexible tube 9 which is adapted to be connected with a water fixture so that the water can be continuously run into the tray and drawn off through the spigot m which is left open. 70

A suitable stand 10 will be employed to support the tray when in use, that shown being of special construction and forming the subject of an application for United States patent filed by me of an even date herewith, Serial No. 466,653. 75

This developing tray forms part of a portable outfit for photographers by means of which pictures can be taken, developed and fixed outdoors, the plate after exposure being transferred to the developing tray, the transfer being effected in a portable dark room 85 such as forming the subject matter of an application filed by me of even date herewith, Serial No. 466,654.

Having thus described my invention, what I claim, and desire to secure by Letters Patent, is—

1. A photographer's developing tray composed of a lower section having an inner ledge, and having a plate opening in one side just above the said ledge, a strip on the three sides of the said ledge remote from the side having the plate opening, a door hinged to the side and having a strip to enter the said plate opening to force the plate to place, an upper section having a flexible strip at its lower end to engage with the plate to be developed and obtain a close joint, and clamping devices to secure the sections together, substantially as described for the purpose set forth. 95

2. A photographer's developing tray composed of an upper section closed at the top by a colored glass and open at the bottom, and subdivided into two or more compartments, by vertical partitions, funnels and spigots for each compartment attached to the said section near the lower end thereof, the flexible strip at the bottom edge of the said section to engage with the plate to be developed and obtain a close joint, a lower section 115 closed at the bottom by a colored glass, and having an inner ledge and a plate opening i in a side for each compartment in the upper section, a strip t on the three sides remote from the side having the opening i, a door R 120 having a strip to enter the opening i and force the plate to proper place, the sides of the said lower section having slots to receive the said spigots and funnels and clamping devices to secure the said two sections together and 125 clamp the plate between the lower end of the upper section and the said inner ledge, substantially as set forth.

This specification signed and witnessed this 15th day of March, 1893.

ARTHUR D. F. RANDOLPH.
